DESIGN FOR A BOOT

Vance P. Britton, New York, N. Y.

Application September 7, 1944, Serial No. 115,216

Term of patent 14 years

(Cl. D7—7)

To all whom it may concern:

Be it known that I, Vance P. Britton, a citizen of the United States and a resident of New York, in the county of New York, State of New York, have invented a new, original, and ornamental Design for Boot, of which the following is a specification, reference being had to the accompanying drawing, forming part thereof.

Fig. 1 is a side elevational view of a boot, showing my new design, the opposite side presenting

substantially the same appearance as the side shown.

Figure 2 is a bottom view of the same.
Figure 3 is a front elevation of the same.
Figure 4 is a rear elevation of the same.

I claim:

The design for a boot, substantially as shown and described.

VANCE P. BRITTON.
